INVENTOR

ATTORNEY

UNITED STATES PATENT OFFICE.

ERNEST GAUDET, OF HYDE PARK, MASSACHUSETTS.

MAT.

Application filed October 29, 1926. Serial No. 145,059.

This invention relates to floor coverings, primarily adapted for use in connection with plumbing fixtures to prevent the floor from becoming wet and from excessive wear.

5 Another object of the invention contemplates means for adapting the mat upon the particular fixture.

More specifically stated the invention comprehends a retaining element carried by the 10 adapting means for anchoring the mat upon the fixture.

With the above and other objects in view, the invention further includes the following 15 novel features and details of construction, to be hereinafter more fully described, illustrated in the accompanying drawings and pointed out in the appended claims.

In the drawings:—

20 Figure 1 is a side elevation of a fixture with the present invention applied thereto.

Figure 2 is a sectional view taken on line 2—2 of Figure 1.

25 Figure 3 is a view taken on line 3—3 of Figure 2 illustrating the application of the retaining element when used in conjunction with the fixture.

Referring to the drawing in detail, wherein like characters of reference denote corresponding parts, the reference character 10 indicates a plumbing fixture which in this instance appears as a toilet bowl. Said bowl is provided with an enlarged base portion 11 seated upon the floor of a room.

30 The invention consists of a floor covering or mat, such as indicated at 12, which is provided with a serrated upper surface and a series of suction cups 13 formed within its under side for engagement with the floor surface to prevent said mat from becoming 35 displaced. Said mat is provided with an

upstanding flange portion 14 upon one side thereof and converging over the base portion 11 of the bowl 10, substantially as illustrated in Figures 1 and 3 of the drawings. Said flange portions is of such configuration as 45 to receive a portion of the base portion and adjacent portion of the bowl body.

A U-shaped retaining element embodying resilient propensities is positioned within the upper edge of said upstanding flange portion 14 to rigidly engage the aforementioned portion of the base and body of the bowl to prevent movement of said mat subsequent to the application thereof.

The invention is susceptible of various 55 changes in its form, proportions and minor details of construction, and the right is herein reserved to make such changes as properly fall within the scope of the appended claims.

Having described the invention what is claimed is:—

1. A mat for use in connection with plumbing fixtures having a serrated upper surface, an upstanding flange portion carried by the mat extended over the base of the fixture, and a multiplicity of suction cups carried upon the under surface of the mat.

2. A mat adapted for use in connection with plumbing fixtures comprising a serrated upper surface and a multiplicity of suction cups upon its under side, an upstanding flange portion carried by the mat extended over the base of the fixture, and a U-shaped retaining element carried by the 70 upstanding flange adapted to frictionally engage the fixture to prevent displacement of the mat.

ERNEST GAUDET.
